THERMOCHROMIC ADHESIVE THERMOMETER

Philip L. Van Kersen, P.O. Box 40423,
Indianapolis, Ind. 46240

Filed Nov. 12, 1973, Ser. No. 414,745

Term of patent 14 years

Int. Cl. D10—04

U.S. Cl. D10—57

Fig. 1

Fig. 2

Fig. 3

FIG. 1 is a front elevational view of a thermochromic adhesive thermometer showing my new design;

FIG. 2 is a rear elevational view thereof;

FIG. 3 is a side elevational view, the other sides not shown are identical thereto.

I claim:

The ornamental design for a thermochromic adhesive thermometer, as shown and described.
